UNITED STATES PATENT OFFICE.

GEORGE WASHINGTON BAMFORD, OF RICHMOND, VIRGINIA, ASSIGNOR TO
AUGUST F. CORDES, OF SAME PLACE.

CURTAIN FIXTURE OR SUPPORT.

SPECIFICATION forming part of Letters Patent No. 571,184, dated November 10, 1896.

Application filed December 4, 1895. Serial No. 570,997. (No model.)

To all whom it may concern:

Be it known that I, GEORGE WASHINGTON BAMFORD, a citizen of the United States, and a resident of Richmond, in the county of Henrico and State of Virginia, have invented certain new and useful Improvements in Curtain Fixtures or Supports, of which the following is a specification, reference being had to the accompanying drawings, forming a part thereof, in which similar letters of reference indicate corresponding parts.

This invention relates to curtain-fixtures or to means for supporting a curtain, portière, or other article, and the object thereof is to provide a device of this class which may be connected with the upper portion of a window-frame or the frame of sliding doors or other supports, a further object being to provide a device of this class which is adapted to be connected with window-frames or other supports of different widths and in which the length of the fixture or other article by which the curtain is supported may be longitudinally adjusted; and with this and other objects in view the invention consists in the construction, combination, and arrangement of parts hereinafter described and claimed.

The invention is fully disclosed in the following specification, of which the accompanying drawings form a part, in which—

Figure 1 is a front view of a window-frame provided with my improved fixture; Fig. 2, a plan view thereof; Fig. 3, a side view; and Fig. 4, a view similar to that of Fig. 3, showing a part of the support in section.

In the drawings, forming part of this specification, A represents an ordinary window-frame composed of sides and top and bottom pieces, and secured to the upper portion thereof is my improved curtain fixture or support, which consists of two similar rods or bars B, having depending ends or arms C, which are formed by bending the rods B backwardly and downwardly and which are secured to the frame or supported thereon by keepers D, through which the depending ends or arms C are passed, as clearly shown, and the lower ends of said ends or arms are provided with nuts or burs E.

The rods or bars B are connected by means of a tubular section F, into which said rods or bars are passed, as clearly shown in Figs. 1 and 2, and said tubular section constitutes the central portion of the fixture or support, and, as will be understood, the length of said fixture or support may be regulated at all times by sliding said rods or bars inwardly or outwardly in said tubular section, as desired, and, as will also be apparent, this device, by reason of this form of construction, is adapted to be connected with window-frames of different widths or with the frames of passageways between rooms or any desired support.

In practice the curtain, portière, or other article is connected with the rods or bars B and to the tubular section F in any desired manner, the means by which this connection is made forming no part of this invention. It will thus be seen that I accomplish the object of my invention by means of an effective device, which is simple in construction and operation and comparatively inexpensive, and my invention is not limited to the exact form, construction, and arrangement of parts herein described, and I therefore reserve the right to make all such alterations therein and modifications thereof as fairly come within the scope of the invention.

Having fully described my invention, its construction, and operation, I claim as new and desire to secure by Letters Patent—

The combination in a curtain fixture or support of two rods, a tubular section adapted to fit upon said rods and slide thereon, said rods being bent at right angles to the window-frame and then again bent downwardly parallel with said window-frame, and journal-brackets on the frame wherein the said rods are secured, and a bur or nut secured to the end of said rods, substantially as set forth.

In testimony that I claim the foregoing as my invention I have signed my name, in presence of the subscribing witnesses, this 23d day of November, 1895.

GEORGE WASHINGTON BAMFORD.
